UNITED STATES PATENT OFFICE.

EDWIN L. WILLSON, OF FARMINGTON, CONNECTICUT.

ELECTRIC FURNACE.

Application filed October 16, 1922. Serial No. 594,831.

To all whom it may concern:

Be it known that I, EDWIN L. WILLSON, a citizen of the United States, residing at Farmington, county of Hartford, and State of Connecticut, have invented new and useful Improvements in Electric Furnaces, of which the following is a full, clear, and exact specification.

My invention relates to furnaces and refers particularly to electrically heated furnaces.

The object of my device is an internally electrically heated rotary furnace capable of a continuous process of heating articles automatically at any desired temperature for any desired period of time either with, or without, the presence of air, carbonizing gases, inert or other gases.

Considerable difficulty has been experienced in obtaining uniform temperature, hardness, bluing and other similar results upon a plurality of small articles, due to the difficulty in obtaining an accurately uniform temperature and duration of treatment in the heating process.

As the desired results depend upon the temperature and time of heat treatment and are affected by any variation thereof, it is evident that uniform results can be obtained only when each and every article has been subjected to the same heating temperature for the same length of time.

The difficulty of thus treating a large number of such small articles, as bearing balls, chain links and other small parts, is evident and a device capable of accomplishing these results is a most valuable advance in the heat treatment of metal articles.

The device of my invention is capable of producing all of these desirable results in a most efficient and economical manner and comprises in a general way a rotary furnace, electrically heated internally, the interior heat of the furnace being automatically controlled and the process of treatment being preferably continuous.

The accompanying drawings, illustrating modified forms of the device of my invention and are given for the purpose of more clearly defining my invention, similar parts being designated by similar numerals.

Figure 1 is a cross-section through the line 1—1 of Figure 2, the dot-and-dash lines illustrating the position of the driving mechanism.

Figure 2 is a cross-section through the line 2—2 of Figure 1 showing a portional end view of Figure 1.

Figure 3 is a cross-section through the line 3—3 of Figure 1.

Figure 4 is a cross-section through the line 4—4 of Figure 1.

Figure 5 is a vertical cross-section of a modified form of the device of my invention.

The particular form of the device of my invention, shown in Figures 1, 2, 3 and 4 of the accompanying drawings, comprises a bed 10 carrying the supports 11, 11, within the bearings 12, 12 of which is the revolute shaft 13. Fixedly attached to the shaft 13 is the toothed worm wheel 14 and the frictional flanged bearing wheel 15. The worm wheel 14 meshes with the worm 16, carried by the bearings 17, 17, the shaft 18 of the worm 16 being connected with a source of revolute power, not shown.

Each of the other three corner portions of the bed 10 carries brackets 19, 19 having bearings 20, 20 in which is a shaft 21 carrying a freely revolute flanged idler 22.

The legs 23, 23 carry the pillow blocks 24, 24 which support the non-revolute tubular member 25. A hopper 26 opens into the tubular member 25 and a pipe 27, connected with a source of suitable gas supply, not shown, passes through a portion of the tubular member 25 and is then bent downwardly within the furnace.

The central portion of the tubular member 25 passes through and carries a plurality of wire carriers 28, 28, composed preferably of heat refractory, electric insulating and heat insulating material, the carriers being maintained in position by a series of supporting rods 29, 29. The wire carriers 28, 28 have a plurality of extended arms 30, 30 to which a wire may be attached by any suitable means.

Revolute around the tubular member 25 is a container composed of the annular front end 31. Fixedly attached to the end 31 by means of bolts 32, 32 is the flat ring 33. Within the interior opening of the ring member 33 is the cylindrical furnace side 34. The other end of the device comprises the annular members 35, 50, 37 fixedly attached to the tubular member 25 which passes through the opening 38 by the member 37.

An arm of the annular member 39 is inserted within an annular recess within a re-

cess within the member 35, the other right angled annular arm of the member 39 being bolted at 40 to the flat ring member 41. The other extremity of the furnace side 25 is supported by the opening within the ring member 41.

Fixedly attached to the interior face of the revoluble furnace side 25 is a helix-shaped member 42 having a central opening 10 to allow of its being spaced from the wire carriers 28, 28.

An opening 43 is formed within the lower portion of the end member 36 and the sides thereof extended into the tubular member 44, the lower extremity of which is below the surface of the oil or other quenching material 45 in the container 46.

The electric heating, or resistant, wire 47 is wound around the wire carrier arms 30, 30 and extends outwardly through the tubular member 25 and is connected with any suitable means for the supply of electrical current, this end of the tube 25 being closed.

A pyrometer 48 is introduced into the tube 44 and a pyrometer 49 is inserted within the working chamber and the latter may be connected to any suitable thermostatic device for the control of a uniform temperature.

The following method is employed in order to prevent, or reduce, the loss by heat radiation:—

The chamber formed within the members 35, 50, 37 is packed with a non-conductor of heat. An annular chamber is formed 35 at the other end of the furnace by means of the plates 51, 52 and 53 and filled with a non-conductor of heat.

An annular plate 54 is fixedly attached to the plate 33, an annular plate 55 is fixedly attached to the plate 41 and a telescopic annular plate 56 is horizontally slidable within the plates 54 and 55 and the chamber thus formed is filled with a non-conductor of heat. This formation allows of horizontal movement due to heat expansion.

An annular plate 57 is attached to the plates 41 and 39 and the chamber thus formed is filled with a non-conductor of heat.

The wire carrier nearest the forward end of the furnace and through which the pipe 27 passes is somewhat different in construction from the others in that it has opening 58 (Figure 4) extending downwardly from the central opening in order to allow of the passage of the pipe 27 and for the introduction of articles to be heated.

The end members 33 and 41 of the furnace body rest upon the frictional wheel 15 and 60 the idlers 22, 22, 22 so that the revolution of the frictional wheel 15 will revolve the furnace body with its attached parts.

The operation of the device as described is as follows:—

Revolute movement is imparted to the

shaft 18, the worm 16, the gear wheel 14, the shaft 13 and the frictional wheel 15, which thus revolves the furnace with its non-conducting covering and attached helix 42, around the tubular member 25 and the wire carriers 28, 28. An electric current is then passed through the resistant wire 47 heating the interior of the furnace to any desired temperature. The objects to be heated, as, for instance, bearing balls 60, 60 are introduced through the hopper 26 and the tubular member 25 from which they drop into the furnace, their passage through the tubular member 25 beyond the point of introduction into the furnace being prevented by the baffle plate 59. The helix 42, during its revolution, carries the balls 60, 60 along the lower portion of the furnace, heating them to any desired temperature and time of treatment dependent upon the temperature of the furnace and the time required for passage therethrough, the latter being controlled by the length of the furnace and the rate of revolution of the helix. The heated balls pass through the opening 43 and the exit pipe 44 into the oil 45, where they are caught by the foraminous basket 61, which can be removed when desired.

It is to be noted that during the heating operation the furnace space, its side wall and the objects therein are subjected to the full effects of the heated wire and any cooling effect, caused to the lower portion of the furnace wall due to heat absorption by the objects, will be counteracted during the remainder of the revolution of the furnace.

Any heating effect, which will be small under proper conditions, caused by the tubular member 25 will act as a preheater for the introduced objects.

The air in the furnace may be partially, or completely, removed by the vapors arising from the oil 45, due to the introduction of the heated objects, the fumes arising through the pipe 44 into the furnace, thus driving the air outwardly through the tubular member 25.

My device is also admirably adapted for carbonizing processes, in which case a suitable carbonaceous gas may be introduced through the pipe 27, or a suitable carbonizing compound may be introduced into the furnace, the heat of which will cause an evolution of the carbonaceous gas.

The form of my device, described above, is suitable for the heating of small objects moved within the furnace by means of the described helix, but a modification is desirable where the device is to be applied to the heating of objects which, on account of their shape or size, cannot be readily moved through the furnace by the helix movement.

A modified form of a device for the last described articles is shown in Figure 5 in

which the general form of the furnace is similar to that previously described, except that the helix 42 is removed, a hinged door 70 is introduced at one end of the furnace 5 for purposes of introducing the articles and a hinged door 71 is introduced at the other end of the furnace for purposes of withdrawal of the articles after the heating treatment and the end 35, 36, 37 is replaced 10 by the annual end 72. Proper insulating devices may be employed as desired, similar to those shown in the prior figures.

It is evident that means other than the disclosed helix may be employed for producing a movement of the articles through the furnace.

The degree of applied heat and the duration of the treatment naturally depend upon the objects treated and the results desired 20 and my device is of such construction that it can be readily adapted to any desired process of operation and maintained under uniform conditions during the treatment of any desired number of articles.

25 By "electric wire" as used in my specification and claims I mean any wire, ribbon or other electrical constructing means, having electric resistance under the conditions of employment to produce the desired heat.

30 My device, therefore, presents many novel and valuable features for the heat treatment of small metallic articles and parts.

I do not limit myself to the particular 35 size, shape, number, arrangement or material of parts, as shown and described, as they are given simply as an example for the clearer explanation of the device of my invention.

What I claim is:—

40 1. In an internally electrically heated rotary furnace, in combination, a revolute furnace having an opening for the introduction of material and an opening for the removal of said material, means for revolving the furnace, wire carrying means within the furnace and a wire carried thereon and extended outwardly of the furnace.

45 2. In an internally electrically heated rotary furnace, in combination, a revolute furnace having an opening for the introduction of material and an opening for the removal of said material, means for revolving the furnace, stationary wire carrying means within the furnace and a wire carried thereon and extended outwardly of the furnace.

50 3. In an internally electrically heated rotary furnace, in combination, a revolute furnace having an opening for the introduction of material and an opening for the removal of said material, means for revolving the furnace, wire carrying means within the furnace, a wire carried thereon and extended outwardly of the furnace and 55 means within the furnace whereby material

introduced into the furnace through one opening will be conveyed to the other opening.

4. In an internally electrically heated rotary furnace, in combination, a revolute 70 furnace having an opening for the introduction of material and an opening for the removal of said material, means for revolving the furnace, wire carrying means within the furnace, a wire carried thereon and 75 extended outwardly of the furnace and means within the furnace whereby the revolution of the furnace will cause material introduced through the opening to be delivered through the other opening.

5. In an internally electrically heated rotary furnace, in combination, a revolute furnace having an opening for the introduction of material and an opening for the removal of said material, means for revolving the furnace, wire carrying means within the furnace, a wire carried thereon and extended outwardly of the furnace and a helix shaped member within the furnace and carried thereby capable of conveying material 80 from one end of the furnace to the other during the revolution of the furnace.

6. In an internally electrically heated rotary furnace, in combination, a stationary shaft, a furnace revolute around the shaft, 85 means for revolving the furnace, means for introducing material into the furnace, means for the removal of material from the furnace, wire carriers within the furnace and spaced from the side thereof, a wire carried thereby and extending outwardly of the furnace and means within the furnace for the removal of introduced material during the 90 revolution of the furnace.

7. In an internally electrically heated rotary furnace, in combination, a stationary shaft, a furnace revolute around the shaft, means for revolving the furnace, means for introducing material into the furnace, means within the furnace for removing material from the furnace, a plurality of electric insulators capable of maintaining a wire 100 and a wire carried thereby and extending outwardly of the furnace.

8. In an internally electrically heated rotary furnace, in combination, a hollow shaft, a furnace revolute around the shaft, means for revolving the furnace, means external of the furnace for introducing material through the shaft into the furnace, opening means for allowing the removal of material from the furnace, electric insulators carried by the shaft and capable of maintaining a wire and an electric wire carried thereby and extending outwardly through 110 the shaft.

9. In an internally electrically heated rotary furnace, in combination, a hollow shaft, a furnace revolute around the shaft, means for revolving the furnace, means external of 115

- the furnace for introducing material through the shaft into the furnace, opening means for allowing the removal of material from the furnace, electric insulators carried by the shaft and capable of maintaining a wire, an electric wire carried thereby and extending outwardly through the shaft and means whereby material introduced into the furnace through one opening will be conveyed to the other opening. 10. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, electric insulators carried by the shaft and capable of maintaining a wire, an electric wire carried thereby and extending outwardly through the shaft and means whereby the revolution of the furnace will cause material introduced through the opening to be delivered through the other opening. 11. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, electric insulators carried by the shaft and capable of maintaining a wire, an electric wire carried thereby and extending outwardly through the shaft and a helix shaped member within the furnace and carried thereby capable of conveying material from one end of the furnace to the other during the revolution of the furnace. 12. In an internally electrically heated rotary furnace, in combination, a revoluble furnace having an opening for the introduction of material and an opening for the removal of said material, means for revolving the furnace, means for introducing a gas into the furnace during its revolution, wire carrying means within the furnace and a wire carried thereon and extended outwardly of the furnace. 13. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, means for introducing a gas into the furnace during its revolution, electric insulators carried by the shaft and capable of maintaining a wire and an electric wire carried thereby and extending outwardly through the shaft. 14. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, means for introducing a gas into the furnace during its revolution, electric insulators carried by the shaft and capable of maintaining a wire, an electric wire carried thereby and extending outwardly through the shaft and means within the furnace whereby material introduced into the furnace through the opening will be conveyed to the other opening. 15. In an internally electrically heated rotary furnace, in combination, a stationary shaft, a furnace revoluble around the shaft, means for revolving the furnace, means for introducing material into the furnace, compensating means for the longitudinal expansion of the furnace due to the heating thereof, wire carriers within the furnace and spaced from the side thereof, a wire carried thereby and extending outwardly of the furnace and means within the furnace for the removal of introduced material during the revolution of the furnace. 16. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, compensating means for the longitudinal expansion of the furnace due to the heating thereof, electric insulators carried by the shaft and capable of maintaining a wire and an electric wire carried thereby and extending outwardly through the shaft. 17. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, compensating means for the longitudinal expansion of the furnace due to the heating thereof, electric insulators carried by the shaft and capable of maintaining a wire, an electric wire carried thereby and extending outwardly through the shaft and means whereby material introduced into the furnace through one opening will be conveyed to the other opening. 18. In an internally electrically heated rotary furnace, in combination, a hollow shaft, a furnace revoluble around the shaft, means for revolving the furnace, means external of the furnace for introducing material through the shaft into the furnace, opening means for allowing the removal of material from the furnace, compensating means for the longitudinal expansion of the furnace due to the heating thereof, electric insulators carried by the shaft and capable of maintaining a wire, an electric wire carried thereby and extending outwardly through the shaft and means whereby material introduced into the furnace through one opening will be conveyed to the other opening.

- rial through the shaft into the furnace, opening means for allowing the removal of material from the furnace, compensating means for the longitudinal expansion of the furnace due to the heating thereof, electric insulators carried by the shaft and capable of maintaining a wire, an electric wire carried thereby and extending outwardly through the shaft and means whereby the revolution of the furnace will cause material introduced through one opening to be delivered through the other opening. 70
19. In an internally electrically heated rotary furnace, in combination, a revolute furnace having an opening for the introduction of material and an opening for the removal of said material, means for revolving the furnace, wire carrying means within the furnace, a wire carried thereon and extended outwardly of the furnace and an external covering of heat insulating material carried by the furnace. 80
20. In an internally electrically heated rotary furnace, in combination, a hollow stationary shaft, a furnace revolute around the hollow shaft, means for revolving the furnace, means external of the furnace for introducing material through the shaft into the furnace, means for allowing the removal of material from the furnace, a plurality of electric insulators carried by the shaft and spaced from the side of the furnace, a wire wound around the insulators and carried thereby, the extremities of the wire extending outwardly of the furnace and an external covering of heat insulating material carried by the furnace. 90
21. In an internally electrically heated rotary furnace, in combination, a hollow stationary shaft, a furnace revolute around the hollow shaft, means for revolving the furnace, means external of the furnace for introducing material through the shaft into the furnace, means for allowing the removal of material from the furnace, means whereby material introduced into the furnace at one end will be conveyed to the other end, a plurality of electric insulators carried by the shaft and spaced from the side of the furnace, a wire wound around the insulators and carried thereby, the extremities of the wire extending outwardly of the furnace and an external covering of heat insulating material carried by the furnace. 100
22. In an internally electrically heated rotary furnace, in combination, a hollow stationary shaft, a furnace revolute around the hollow shaft, means for revolving the furnace, means external of the furnace for introducing material through the shaft into the furnace, means for allowing the removal of material from the furnace, means whereby the revolution of the furnace will cause material to be conveyed from one end of the furnace to the other, a plurality of 110
- electric insulators carried by the shaft and spaced from the side of the furnace, a wire wound around the insulators and carried thereby, the extremities of the wire extending outwardly of the furnace and an external covering of heat insulating material carried by the furnace. 120
23. In an internally electrically heated rotary furnace, in combination, two stationary end members, a side member revolute between the end members and forming a furnace chamber therewith, means for revolving the side member, means for introducing material into the furnace, means for allowing of the removal of a material from within the furnace and means internal of the furnace for electrically heating the same. 125
24. In an internally electrically heated rotary furnace, in combination, two stationary end members, a side member revolute between the end members and forming a furnace chamber therewith, means for revolving the side member, means for introducing material into the furnace, revolute means for removing material from within the furnace, means for allowing of the removal of a material from within the furnace and means internal of the furnace for electrically heating the same. 130
25. In an internally electrically heated rotary furnace, in combination, two stationary end members, a side member revolute between the end members and forming a furnace chamber therewith, means for revolving the side member, means for introducing material into the furnace, means whereby the revolution of the side member will cause material to be conveyed from one end of the furnace to the other, means for allowing of the removal of a material from within the furnace, and means internal of the furnace for electrically heating the same. 140
26. In an internally electrically heated rotary furnace, in combination, two stationary end members, a side member revolute between the end members and forming a furnace chamber therewith, means for revolving the side member, means for introducing material into the furnace, a helix shaped member within the furnace and carried thereby capable of conveying material from one end of the furnace to the other during the revolution of the furnace and means internal of the furnace for electrically heating the same. 150
27. In an internally electrically heated rotary furnace, in combination, a stationary hollow shaft, two stationary end members, a side member revolute between the end members and forming a furnace chamber therewith, means for revolving the side member, means external of the furnace for introducing material through the shaft and into the furnace, means for allowing the removal of material from the furnace, elec- 160

- tric insulators within the furnace spaced from the side member and an electric wire carried by the insulators and extending outwardly of the furnace.
28. In an internally electrically heated rotary furnace, in combination, a stationary hollow shaft, two stationary end members, a side member revoluble between the end members and forming a furnace chamber therewith, means for revolving the side member, means external of the furnace for introducing material through the shaft and into the furnace, means for allowing the removal of material from the furnace, electric insulators within the furnace spaced from the side member, an electric wire carried by the insulators and extending outwardly of the furnace and means whereby material introduced into the furnace through one opening will be conveyed to the other opening.
29. In an internally electrically heated rotary furnace, in combination, a stationary hollow shaft, two stationary end members, a side member revoluble between the end members and forming a furnace chamber therewith, means for revolving the side member, means external of the furnace for introducing material through the shaft and into the furnace, means for allowing the removal of material from the furnace, electric insulators within the furnace spaced from the side member, an electric wire carried by the insulators and extending outwardly of the furnace and means whereby the revolution of the side member will cause material introduced through the opening to be delivered through the delivery end.
30. In an internally electrically heated rotary furnace, in combination, two stationary end members, a side member revoluble between the end members and forming a furnace chamber therewith, means for revolving the side member, means for introducing material into the furnace, means for allowing of the removal of a material from within the furnace, means internal of the furnace for electrically heating the same and an external covering of heat insulating material carried by the device.
31. In an internally electrically heated rotary furnace, in combination, two sta-
- tionary end members, a side member revoluble between the end members and forming a furnace chamber therewith, means for revolving the side member, means for introducing material into the furnace, means for allowing of the removal of a material from within the furnace, means internal of the furnace for electrically heating the same and an external covering of heat insulating material carried by the device.
32. In an internally electrically heated rotary furnace, in combination, a stationary hollow shaft, two stationary end members, a side member revoluble between the end members and forming a furnace chamber therewith, means for revolving the side member, means external of the furnace for introducing material through the shaft and into the furnace, means for allowing the removal of material from the furnace, electric insulators within the furnace spaced from the side member, an electric wire carried by the insulators and extending outwardly of the furnace and means whereby the revolution of the side member will cause material to be conveyed from one end of the furnace to the other.
33. In an internally electrically heated rotary furnace, in combination, a stationary hollow shaft, two stationary end members, a side member revoluble between the end members and forming a furnace chamber therewith, means for revolving the side member, means external of the furnace for introducing material through the shaft and into the furnace, means for allowing the removal of material from the furnace, electric insulators within the furnace spaced from the side member, an electric wire carried by the insulators and extending outwardly of the furnace, and means whereby the revolution of the side member will cause material to be conveyed from one end of the furnace to the other end and delivery therethrough.

Signed at New York city, in the county of New York and State of New York, this 4th day of October, 1922.

EDWIN L. WILLSON.
